UNITED STATES PATENT OFFICE.

GEORGE A. STREETT, OF CLEVELAND, OHIO.

LOOSE-LEAF BINDER.

1,106,479.

Specification of Letters Patent. Patented Aug. 11, 1914.

Application filed April 30, 1914. Serial No. 835,361.

To all whom it may concern:

Be it known that I, GEORGE A. STREETT, a citizen of the United States, residing at Cleveland, in the county of Cuyahoga and State of Ohio, have invented a certain new and useful Improvement in Loose-Leaf Binders, of which the following is a full, clear, and exact description.

This invention relates to a loose leaf binder, the object of the invention being to provide a cheap, easily manufactured construction which will effectively operate for the purpose intended.

Generally speaking, the invention comprises the elements and the combinations thereof recited in the accompanying claims.

Reference should be had to the accompanying drawings forming a part of this specification, in which—

20 Figure 1 is a perspective view showing the binder. Fig. 2 is a perspective view showing the flexible strip employed in the binder; and Fig. 3 is a transverse section through a portion of the binder, as shown in Fig. 1.

25 In the drawing, the cover is represented at 1. This may be formed of one sheet folded, or it may be formed of two sheets which are folded in such manner that the retaining or backing strip about to be described may be

30 engaged and hold the same.

In Fig. 2 there is shown a retaining or backing strip 2 which is formed of light flexible material, and I have found brass to be very appropriate material, although I do not necessarily limit myself thereto. The strip 2 has a series of tongues 3 projecting therefrom, and preferably these tongues are formed by severing the same along all the edges except one, so that the tongue may be bent from the body of the strip along the uncut portions. The strip is also at its ends provided with upturned tongues 4. That is, tongues 3 and 4 are adapted to engage the cover adjacent the fold therein. The tongues 3 perforate the cover and may be folded down upon the cover to hold the same, while the tongues 4 extend around the edges of the cover and fold down upon the same. Thus it will be seen that the strip 2 is held to the 50 cover not only at the ends, but at points throughout the length of the strip. If desirable, I may employ a strip of heavy paper material or similar substance, as indicated at 5. When the strip is used, it will be clear 55 that the end tongues 4 are folded around

the end of this strip, while the intermediate tongues 3 perforate the strip 5, and are bent to engage with it. From the strip 2 there are upwardly projecting retaining members 6. In the drawing I have shown two, 60 although, if desired, there may be more. These members 6 are adapted to perforate the cover, as well as the strip 5, if the same be used, and to receive perforated sheets of paper which may be threaded upon them, 65 the members being bent back, thereby to retain these loose sheets within the cover and thus bind them together. These members 6, themselves, are preferably formed by severing the same from the body of the strip 2. 70 As will be seen, each retaining member really consists of two pieces 6^a and 6^b,—these being severed from portions of the material forming the strip 2, except for a piece of material 7 which lies between them. When the 75 pieces 6^a and 6^b are bent away from the strip 2, one of the pieces, as represented at 6^a, is folded in part against the strip 2. This renders the piece 6^a somewhat shorter than the piece 6^b, and permits a ready separation of 80 the pieces that they may be folded into a substantially parallel position with the strip 2 when a loose leaf is threaded upon the retaining member.

The strip 2 may be prepared as just indicated by suitably arranged dies cutting the strip. This class of work may be accomplished with rapidity and at small expense. It will therefore be apparent that I have produced an inexpensive loose leaf binder 90 of few parts and compactly arranged.

Having thus described my invention, I claim:

1. A loose leaf binder comprising a folded cover, a backing strip engaging the cover adjacent the fold, said strip being provided with tongues, certain of the tongues perforating the cover, and all of the tongues being bent to retain the cover to the said strip, and flexible projecting members carried by the strip extending from the strip, 100 said members being adapted to engage loose leaves.

2. A loose leaf binder comprising a folded cover, a backing strip engaging the cover, 105 tongues formed from a portion of said strip and bent therefrom, certain of said tongues being adapted to perforate the cover, and all of the tongues being bent to retain the cover to the strip, and flexible projecting 110

members carried by the strip and extending therefrom, said members being adapted to engage and retain loose leaves.

3. A loose leaf binder comprising a folded cover, a backing strip having tongues, certain of said tongues being cut from the body of the strip, the said tongues being bent away from the strip, certain of the tongues perforating the cover, and all of the tongues being bent to retain the cover to the strip, and flexible members formed by severing the same from a portion of the strip, the said members being adapted to engage and retain loose leaves.
4. A loose leaf binder comprising a folded cover, a backing strip having tongues formed

by severing a portion of the body of the strip, and end tongues formed by bending the ends of the strip, the end tongues being adapted to fold around the adjacent edges of the cover, the intermediate tongues being adapted to perforate the cover, and bent to retain the cover to the strip, and flexible members carried by the strip extending therefrom, said members being adapted to engage and retain loose leaves.

In testimony whereof, I hereunto affix my signature in the presence of two witnesses.

GEORGE A. STRETT.
